United States Patent Office

Des. 180,997

Patented Sept. 17, 1957

180,997

BASKET FOR BERRIES OR THE LIKE

Walton B. Crane, South Pasadena, Calif., assignor to Allied Plastics Company, Los Angeles, Calif.

Application February 18, 1957, Serial No. 44,885

Term of patent 14 years

(Cl. D58—4)

Figure 1 is a perspective view of a basket for berries or the like, showing my new design; and

I claim:

The ornamental design for a basket for berries or the like, substantially as shown.
